UNITED STATES PATENT OFFICE

STEPHEN F. BOHM, OF CICERO, ILLINOIS

ANCHOR AND REEL THEREFOR

Application filed April 2, 1928. Serial No. 266,529.

This invention relates to improvements in boat anchors and reels therefor.

The principal object of the invention is to provide an improved anchor having drag arms arranged to be folded into compact relation with respect to the body of the anchor for convenience in carrying or storing the same when not in use.

Another object is to provide an anchor the drag arms of which will automatically be moved to extended or operative position by the weight of the anchor when suspended by an anchor line and will be held in such position by the tugging of the boat upon the said line.

A further object of the invention is to provide an improved reel of sturdy, compact construction which may be temporarily or permanently attached to the boat in vertical or horizontal position and which has a locking device for locking the winding members against rotation.

Further objects relate to various features of construction and arrangement of parts which will be apparent from a consideration of the following specification and accompanying drawings, wherein:

Figure 1 is side elevation of the reel shown attached in horizontal position to the side or rear end of a boat by a readily detachable clamping device.

Figure 2 is an elevation of the reel on the clamp side thereof.

Figure 3 is a sectional view taken on a horizontal line through the center of Figure 1.

Figure 4 are detached details illustrating features of the locking mechanism.

Figure 5 is a broken perspective view showing the clamping device.

Figure 6 illustrates the reel attached to a side of boat by a bolt, the clamp lever having been discarded.

Figure 7 is an elevation of my improved anchor, the drag arms being in folded relation.

Figure 8 is a longitudinal sectional view of the anchor.

Figure 9 is a transverse sectional view taken on line 9—9 of Figure 8.

In the drawings the 10, 11 are cup shaped

side plates provided with ears 12 between three pairs of which extend spacing tubes 13 and bolts 14 for securing the plates in spaced relation. Between the fourth pair of ears 15 is a roller 16 rotatable on the bolt 17 over which roller the anchor line 18 passes when the anchor is raised or lowered.

Centrally secured to the outer surface of each plate 10, 11 is a disk 19 having a number of pressed studs 20 which pass through corresponding holes in the plates, the studs being riveted over on their inner ends to secure the disks to the plates. The disks 19 form bearings for the reduced ends 21, of the reel shaft 22 as shown clearly in Figure 65

3. Secured to the shaft 22 against shoulders 23 are the reel disks 24 which rotate with the shaft 22 and confine the chain 18 on the large central drum portion 25 of the shaft. The disks 24 are housed within the peripheral flanges 10^a, 11^a of the respective plates 10, 11 which arrangement prevents the line 18 from slipping over the disks when the reel is nearly full or when the line comes in at an angle. A hole 26 is provided in the shaft for attaching the chain. Between the reel disks 24 and the respective plates 10, 11 are disposed spacing washers 27 which prevent lateral movement of the winding mechanism which is actuatable by a crank 28 secured to the threaded end 29 of the shaft 22 by a nut 30.

As shown in Figure 3 the reel disks 24 are centrally depressed to a plane slightly inwardly of the plane of the outer rim or flange portion 24^a. The curved connecting portions 31 of the disks are provided with openings 32 which form part of the locking mechanism previously referred to. Both disks 24 are shown provided with such openings 32 but it will be understood that only the disk 24 adjacent the plate 10 need be so formed but as the disks as at present made are formed by the same die the openings appear in both.

A locking slide comprising a manually operable angular member 33, is secured by rivets 34, 35 to two small plates 36, 37 as shown in Figure 4. The plate 36 slides in an opening 38 provided in plate 10 while the inner slide plate 37 overlaps the said opening and 100

prevents withdrawal of the locking slide. The rivet 34 may be formed as a stud at its inner end which is slidable into any one of the openings 32 in the reel disk 24 to lock the reel against rotation as will be clear. Thus the user can wind up the reel to raise the anchor and push the slide lever 33 into locking relation and the anchor will be retained in the desired position. When the anchor has been lowered the reel can be similarly locked to prevent giving out more line as will be apparent.

The reel is provided with a mounting plate 39 which is secured by means of two U shaped brackets 40 to two adjacent bolts 14 as shown in Figure 1. The plate 39 has an opening 41 for receiving a bolt 42 which also passes through an opening in the angular clamp member 43, the upper end of which is reduced to form an extension 44 which passes loosely into a second opening 45 in the plate 39. By means of a nut 46 the clamp 43 can be forced against the side of boat or a boat seat for detachably securing the reel in place.

25 When desired the plate 43 may be dispensed with and the reel secured to the side of a boat by the bolt 42 as shown in Figure 6.

The anchor shown in Figures 7, 8 and 9 has a centrally bored body 46 provided with a recess 47 in its lower end. The lower end is also provided with pairs of ears 48 between each pair of which is pivoted a drag arm 49, preferably three in number. The arms are curved or arcuate as shown and are movable on their pivots to the position shown in Figure 7. When in this inoperative position the anchor can be transported conveniently or placed in a relatively small place, as under the seat of a boat.

40 Passing through the central passage of the body 46 is a slidable rod 50 having an enlarged upper end 51 provided with an opening 52 for attaching the anchor line 18. To the lower end of the rod is secured a plate 53 which is adapted to bear against the inner rounded ends of the drag arms 49. As will be apparent from the above description when the anchor is suspended by the anchor line attached to the rod 50, the weight of the body 46 will force the arms 49 outwardly to the operative position indicated by dotted lines in Figure 8, in which position the arms will dig in or drag on the bottom of the lake or river and anchors the boat. Should the boat tend to move, the tugging on the anchor line will cause the plate 53 to exert pressure on the inner ends of the arms 49 and move the free ends away from the body 46 to the dotted line position, in case the arms have become folded against the body while resting on the river or lake bed.

Although I have shown certain features of my improvements for the purpose of illustration, it will be apparent that various changes 60 may be made therein without departing from

the spirit of the invention as defined in the appended claim.

What I claim is:

An anchor comprising a body provided with a longitudinal passage, integral ears at the lower end of the body, arcuate drag arms pivoted adjacent their lower ends to said ears, said arms being movable on said pivots in a direction to cause the upper ends of the arms to bear against the body member, a rod slidable in said passage and having its upper end enlarged to limit the movement of the same through the passage in one direction, the enlarged portion of the rod having an opening therein for attachment to an anchor line, a plate secured to the lower end of the rod adapted to contact with the lower ends of said arms and to swing the upper ends of the arms away from the body member when the rod is moved in the passage by the anchor line.

In witness whereof I have subscribed my name.

STEPHEN F. BOHM.
